AUTOMATIC CHARGE HEATING CONTROL FOR INTERNAL COMBUSTION ENGINES

Filed Dec. 1, 1924

Fig. 1.

14 - FIG. 3.

D. P. MOLONY. Inventor.

884 *John B. Wright* Attorney

UNITED STATES PATENT OFFICE

DONALD P. MOLONY, OF FLINT, MICHIGAN, ASSIGNOR TO MARVEL CARBURETER COMPANY, OF FLINT, MICHIGAN, A CORPORATION OF INDIANA

AUTOMATIC CHARGE-HEATING CONTROL FOR INTERNAL-COMBUSTION ENGINES

Application filed December 1, 1924. Serial No. 753,175.

This invention relates to an automatic charge heating control for internal combustion engines, the object being to provide means actuated by the oil pressure in the lubricating system of an internal combustion engine controlling the application of the heating medium employed for heating the charge in its passage to the internal combustion engine.

10 Another object of my invention is to provide a control which will allow the full volume of heating medium to pass to the heater when the oil in the lubricating system is cold, so that the full amount of heat will be applied for warming up the internal combustion engine.

Another object of my invention is to provide a control which is exceedingly simple and cheap in construction and one which can 20 be readily applied to any of the well known types of internal combustion engines now in use.

Other and further objects and advantages of the invention will be hereinafter set forth 25 and the novel features thereof defined by the appended claims.

In the drawings,

Figure 1 is a side elevation, partly in section, showing the application of my improved construction of control;

Figure 2 is a detail section through the valve controlling the passage of oil in the pressure chamber; and

Figure 3 is a side elevation showing a 35 slightly modified form of heating chamber.

In the embodiment of my invention as shown in Figure 1, 1 indicates an internal combustion engine, 2 an exhaust manifold having an exhaust pipe 3 connected thereto 40 and 4 the intake manifold to which is connected a carburetor or charge forming device 5, the above description being given so that the operation of my improved construction of automatic control can be readily understood.

The riser of the intake manifold is surrounded by a heating chamber 6, which is connected to an outlet nipple 7 of the exhaust manifold 2 by a pipe 8. The heating 50 chamber is provided with an outlet nipple 9

to which is connected a pipe 10 extending back into the exhaust line 3. This pipe can be dispensed with and the exhaust gases allowed to escape to the atmosphere. Arranged within the outlet nipple 7 of the exhaust manifold 2 is a valve 11, the stem of which is provided with an arm 12 having a series of holes in one of which is adapted to be arranged the hooked end of a rod 13.

The exhaust line pipe 3 is provided with a 60 valve 14, the stem of which carries an arm 15 having a series of holes in which the hooked end of a rod 16 is adapted to be placed.

Arranged in a suitable position on the outside of the internal combustion engine is an 65 oil pressure cylinder 17 which is provided with a piston 18 normally held in raised position by coil spring 19, said piston having piston rods 20 and 21 connected thereto and extending out through the opposite ends of 70 the pressure chamber, said piston rods being connected respectively to the links 13 and 16, whereby the movement of the pistons will control the position of the valves 11 and 14 so as to control the passage of the exhaust 75 gases to the heating chamber 6.

The movements of the valves 11 and 14 are arrested by suitably disposed stops and by the adjustable connection through the rods or links 13 and 16 and the arms 12 and 80 15, the position of the valves can be adjusted for their closing and opening movements for winter or summer setting.

The pressure chamber is provided with an inlet nipple 22 to which is connected a pipe 85 23 extending from a valve casing 24 which is provided with inlet 25 in communication with the oil line system 26 of the internal combustion engine. In the drawing I have shown the oil line system connected directly 90 to a pump 27, but it is, of course, understood that in the application of my invention to an internal combustion engine, the valve casing 24 will be connected in any suitable manner 95 to any of the oil lines of the forced feed lubricating system.

The pipe 23 is connected to the outlet nipple 24 of the valve casing 24 and movably mounted in the top of the valve casing is 100 a piston 28 normally held in position shown

by a coil spring 29, said piston carrying a piston rod 30 which is pivotally connected to a sleeve valve 31 which is adapted to move up and down in the valve casing and close 5 the outlet nipple 24' so as to completely cut off the flow of oil to the pressure chamber.

When the motor is started and the oil is thick, the pressure is greater at low speed so that the oil overcomes the resistance of the 10 spring 29 working against the piston 28 and raises the sleeve valve so as to prevent the flow of oil to the pressure chamber so as to provide a warm-up device.

As the spring 19 of the pressure chamber 15 normally holds the valves in position shown in Figure 1, the entire volume of exhaust gases from the engine passes through the heating chamber 6 so as to heat the charge produced by the charge forming device in its passage to the internal combustion engine. As the speed of the motor increases, the pressure in the oil line of the lubricating system increases and overcomes the resistance of the 20 spring 19 against the piston 18 and the piston 18 moves downwardly so as to close the valve 11 and open the valve 14 which allows the exhaust gases to pass in their normal path of travel out of the exhaust line pipe to the muffler.

30 By the adjustment of the rods 13 and 16, the movement of the valves can be regulated so that they will allow any portion of the entire volume of exhaust gases to be forced out of their natural path of travel through the 35 heating chamber.

The pressure chamber is provided with an outlet pipe 32 leading to the oil sump of the motor so that any leakage of oil past the piston 18 will return to the lubricating system 40 of the internal combustion engine.

In the construction of valve and warming up device as shown in Figure 2, as the motor warms up and the oil thins up, the pressure gradually lowers to such a point that the 45 spring 29 forces the piston downwardly so as to overcome the resistance of the pressure, which opens the outlet 24' so that the pressure chamber is in communication with the oil line of the lubricating system.

50 As the speed of the motor increases, the pressure in the lubricating system increases so that at high speed, the heat is entirely cut off from the heating chamber and as the pressure rises and lowers, the valves are 55 moved to open and closed position to automatically control the application of heat to the charge.

The valve arrangement takes care of the viscosity of the oil in the lubricating system 60 so that in cold weather, the heat is applied irrespective of the speed and as the oil thins out, the valve is opened so as to allow the pressure of the lubricating system to act on the pressure chamber and automatically control 65 the valve.

In the embodiment shown in Figure 3, the construction of all the parts are identical with those disclosed in the preferred form with the exception that the carburetor A is provided with a heating chamber B in communication with the exhaust so that the mixing chamber of the carburetor will be heated so that the charge in its passage to the engine will be heated and it is thought that the description of the preferred embodiment is sufficient for the embodiment shown in Figure 3. 70 75

In the operation of applicant's device when the engine is cold, the oil congeals in pipe 23 and becomes very stiff and when the motor is first started, the resistance offered by this oil is greater than the tension of the spring 29 and the valve is moved into closed position so as to cut off the pressure chamber and the valve remains closed until the lubricant has become heated in the pipe line 23 and in the chamber 17, at which time the spring 29 forces the piston back into its normal position so that the pressure chamber is brought into communication with the lubricating system and the device operates so as to control the application of heat to the heating chamber. This provides a warming up device which only operates when the oil is very stiff or congealed. 80 85 90 95

From the foregoing description it will be seen that I have provided an automatic charge heating control which is operated by the pressure of the oil in the lubricating system of the internal combustion engine whereby the application of heat to the charge in its passage to the internal combustion engine is controlled through the pressure of the lubricating system in which a pressure chamber is in communication with the lubricating system 100 so that as the speed of the motor increases and the oil pressure increases, the application 105 of heat is diminished.

What I claim is:

1. The combination with an internal combustion engine having a forced feed lubricating system, of a heating chamber for heating the charge delivered to said engine, a valve for controlling the admission of heating fluid to said heater and means for actuating said valve controlled by the pressure existing in said forced feed lubricating system. 110 115

2. The combination with an internal combustion engine having a forced feed lubricating system, of a heater arranged to heat the charge in its passage from the charge forming device to the engine, a pressure chamber in communication with said forced feed lubricating system and means movably mounted in said pressure chamber for controlling the application of heat to said heating means. 120 125

3. The combination with an internal combustion engine having a forced feed lubri- 130

cating system, of a heater for heating the charge in its passage to the engine, said heater being in communication with the exhaust, valves for controlling the admission of heating medium to said heater and means connected to said valves actuated by the pressure existing in said forced feed lubricating system.

4. An internal combustion engine having a forced feed lubricating system, means for heating the charge delivered to said engine, a pressure chamber in communication with said forced feed lubricating system, a pressure operated valve for controlling the admission of lubricant to said pressure chamber and means movably mounted in said pressure chamber for controlling the admission of heating medium to said heater.

5. An internal combustion engine having a forced feed lubricating system, a heating chamber arranged to heat the charge in its passage from the charge forming device to the engine, said heater being in communication with the exhaust of said engine, a valve in the exhaust pipe for diverting the exhaust gases through said heater and means actuated by the oil pressure in said lubricating system for actuating said valve.

6. An internal combustion engine having a forced feed lubricating system, means for heating the explosive charge in its passage to the engine, means for delivering a heating medium to said heating means, a valve for controlling the passage of heating medium to said heating means, a pressure chamber in communication with the lubricating system, an automatic valve arranged to control the admission of lubricant under pressure to said pressure chamber and a piston movably mounted in said pressure chamber having a connection with the valve for controlling the admission of heating medium to said heater.

7. An internal combustion engine having a forced feed lubricating system, means for heating the charge delivered to said engine and means for controlling the application of heating medium to said heater actuated by the pressure existing in said forced feed lubricating system.

8. An internal combustion engine having a forced feed lubricating system, means for heating the explosive charge in its passage to the engine, means for controlling the admission of heating medium to said heater, a pressure cylinder having a movable piston connected to said controlling means, a pipe connecting said pressure chamber to the forced feed lubricating system and a pressure actuated valve disposed to control the passage of lubricant to said pressure chamber.

9. An internal combustion engine having a forced feed lubricating system, a heating chamber arranged to heat the explosive charge in its passage to the engine in com-

munication with the exhaust, a valve for controlling the admission of exhaust gases to said heating chamber, a pressure chamber, a piston movably mounted in said chamber having a connection with said valve, said pressure chamber being in communication with the lubricating system and a pressure valve arranged to control the admission of lubricant to said pressure chamber.

10. An internal combustion engine having a forced feed lubricating system, a heating chamber arranged to heat the charge in its passage to the engine, said heating chamber being in communication with the exhaust line of said engine, a valve in the exhaust line, a valve in the intake to said heating chamber, a pressure chamber having a spring actuated plunger connected to said valve, said pressure chamber being in communication with the forced feed lubricating system and adapted to be actuated by the pressure therein for controlling the position of said valves.

In testimony whereof I hereunto affix my signature.

DONALD P. MOLONY.
